UNITED STATES PATENT OFFICE.

HECTOR MCQUARRY, OF ALLANDALE, ONTARIO, CANADA.

AXLE-GAGE.

SPECIFICATION forming part of Letters Patent No. 337,606, dated March 9, 1886.

Application filed December 5, 1885. Serial No. 184,816. (No model.)

To all whom it may concern:

Be it known that I, HECTOR MCQUARRY, of Allandale, in the Province of Ontario and Dominion of Canada, have invented a new and Improved Axle-Gage, of which the following is a full, clear, and exact description.

The object of my invention is to provide certain new and useful improvements in the axle-gage for which United States Letters Patent No. 308,685 were issued to me on the 2d day of December, 1884.

This invention relates to gages employed to determine the bend to be given to an axle, so that the lower supporting-spokes of the "dished" wheel turning thereon will be always plumb, and that said wheel may have the required "gather."

The invention consists in the construction and combination of the various parts of the axle-gage, as will be hereinafter described and claimed.

Reference is to be had to the accompanying drawings, forming part of this specification, in which similar letters of reference indicate corresponding parts in all the figures.

Figure 1 is a plan view of my improved axle-gage. Fig. 2 is a longitudinal elevation of the same. Fig. 3 is a detail plan view of the "dish-rule." Fig. 4 is a cross-sectional view on the line $x-x$, Fig. 2.

The "dish" of a wheel being measured by the ratio of the outward displacement of the outer ends of the spokes beyond the inner ends to the length of said spokes, the downward bend given to the axle at the end to cause the lower spokes to be always plumb, said bend being equal to the dish, is measured in the same terms.

In the drawings, A represents the body or base of the gage, which is provided at one end with the upwardly-projecting head B, having the slot B' formed through it lengthwise. In said slot the hub C² of a bracket-arm, C, is pivoted to swing by the pivot C', and said bracket-arm is curved and extended downward, and is provided on its lower end with a fork, D, between the prongs of which the forked piece E is pivoted, having V-shaped notches in the ends of its prongs F, to adapt said ends to fit on an axle and hold the piece E parallel with the same. On the other end of

the bar A the sliding piece G is held by a set-screw, H, and is provided with the downwardly-projecting part J, notched in its lower end to fit the axle.

On the top of the bar A the plate K is held, which is termed the "dish-rule," and is provided with the longitudinal central line, a, vertically in line with the pivot C' and the notched end of J. At each side of the line a the parallel lines d are provided, and marked to indicate their respective distances from the line a. In this case the lines are one-eighth of an inch apart, and their distances measured by eighths, as shown.

The "spoke-rule" or radius-bar L is mounted on the pivot C', and in a horizontal slot, C³, in the lower part of the bracket-hub C², to swing over the dish-rule K and closely thereto. At its end it is provided with the segmental guide M, the inner edge of which slides on the segmental end edge of the dish-rule, and which guide has its ends M' bent down to form stops, which can strike the side edges of the bar A.

The spoke-rule L is divided at the swinging end into inches and fractions thereof, and the divisions are numbered to denote their respective distances in inches from the center of the pivot C'.

On the bracket-arm the pointer O is formed nearly vertically in line with the piece E, and which projects over the spoke-rule, having the mark W, to which the pointer O normally points. The index end of the pointer swings under a hook-arm, P, extending over the bar A, and provided with gage-marks h h, with which a stud or projection, R, on the pointer can register, and which serve to indicate the forward gather of the axle-arm.

The clamp S, having the screw T, serves to lock the swinging end of the spoke-rule L in place.

The operation is as follows: The gage is placed on a perfectly-straight rod, and the spoke-rule L is placed with its divided edge in coincidence with the central line, a, of the dish-rule and locked in place by the clamp-piece S, holding its curved end piece, M. If the instrument is in adjustment, the index O will point to the mark W, and the button, pin, or stud R will coincide with the central mark,

h. The gage is then adjusted for the dish of the wheel to be mounted on the axle. If, for example, the wheel has one-half an inch dish in twenty-two inches of length of spoke, 5 the spoke-rule is moved outward until the mark twenty-two thereon is fairly even with the line on the dish-rule marked as being one-half an inch from the central line, *a*, in this case No. 4, and then the spoke-rule is 10 locked in this position. Then the gage is placed on the side of the axle whose bend is to be determined, the inner notched prong, *F*, resting against the axle-collar, and said inner prong being nearly vertically in line with the 15 pivot *C*, the bar *A* is supported on and above the main straight part of the axle and parallel therewith and the notched piece *E* rests on and is parallel with the axle-arm. If the pointer does not point to the mark *W* on the 20 spoke-rule, the axle must be heated and set in the usual manner until when the gage is placed thereon the index or pointer *O* points to the mark *W*.

To obtain the required gather the axle is 25 "set," so that when the gage is placed thereon the stud *R* on the pointer *O* will coincide with the outside gather-mark, *h*.

As the gage is a double-scale gage, it can be placed on the forward or rear side of the axle 30 to set for dish and on the bottom or top to set for gather, which is very advantageous when only one side of the axle is approachable.

Having thus described my invention, what I claim, and desire to secure by Letters Patent, 35 is—

1. In an axle-gage, the combination, with the bar *A*, of the slotted head *B* on the same, and the bracket-arm *C*, pivoted in said head and provided with the pointer *O*, extending 40 over the bar *A*, substantially as herein shown and described.

2. In an axle-gage, the combination, with the bar *A*, of the slotted head *B*, the bracket-arm *C*, pivoted in the same, which arm *C* has the pointer *O* formed on one end and has the 45 other end forked, and of the forked notched piece *E*, pivoted in the forked end of the arm *C*, substantially as herein shown and described.

3. In an axle-gage, the combination, with the bar *A*, of the slotted head *B*, the bracket-arm *C*, pivoted in the same and provided with the pointer *O*, and of the spoke-rule *L*, mounted to turn on the pivot of the bracket-arm *C* in the head *B* below said bracket, substantially as herein shown and described. 50

4. In an axle-gage, the combination, with the bar *A*, of the dish-rule *K* on the same, the spoke-rule *L*, pivoted to swing over the dish-rule, and of the bracket-arm *C*, pivoted on the bar *A*, and provided with a pointer swinging above the spoke-rule, substantially as 55 herein shown and described.

5. In an axle-gage, the combination, with the bar *A*, of the dish-rule *K* on the same, the curved arm *P*, extending over the top of 60 the spoke-rule and provided with the marks *h*, the spoke-rule *L*, pivoted to swing over the dish-rule, and of the bracket-arm *C*, pivoted on one end of the bar *A* and provided with the pointer *O*, having the projection or pin *R*, 70 adjacent to the arm *P*, substantially as herein shown and described.

6. In an axle-gage, the combination, with the base or body and the spoke-rule, of the dish-rule *K*, having a longitudinal central line, 75 *a*, and longitudinal parallel lines *d d* at both sides of the said central line, substantially as set forth.

HECTOR MCQUARRY.
